(57) **CLAIM**

The ornamental design for an activity tracker band, as shown and described.

DESCRIPTION

FIG. 1 is a front, left perspective view of an activity tracker band showing our new design.

FIG. 2 is a front view of the activity tracker band of FIG. 1.

FIG. 3 is a rear view of the activity tracker band of FIG. 1.

FIG. 4 is a left side view of the activity tracker band of FIG. 1.

FIG. 5 is a right side view of the activity tracker band of FIG. 1.

FIG. 6 is a top plan view of the activity tracker band of FIG. 1.

FIG. 7 is a bottom plan view of the activity tracker band of FIG. 1.

FIG. 8 is a perspective view of the activity tracker band of FIG. 1 in an alternate, fastened configuration; and,

FIG. 9 is an enlarged partial rear perspective view of the activity tracker band of FIG. 1.

The broken lines in the drawings represent environmental subject matter only and form no part of the claimed design. The ornamental design of the present disclosure is a wrist band for use with an activity tracker module.

1 Claim, 7 Drawing Sheets
